(57) **CLAIM**

The ornamental design for graphite sheet for protecting crucible, as shown and described.

DESCRIPTION

FIG. 1 is a front elevational view of the design, the rear elevational view being the same;

FIG. 2 is an elevational view of one side thereof, the other side being the same;

FIG. 3 is a top plan view thereof;

FIG. 4 is a bottom plan view thereof; and,

FIG. 5 is an enlargement of rectangle 5 as shown in FIG. 1. The broken lines in the drawings are for the purpose of illustrating environmental structure and form no part of the claimed design embodiments.

CERTIFICATE OF CORRECTION

PATENT NO. : D781,942 S
APPLICATION NO. : 29/422300
DATED : March 21, 2017
INVENTOR(S) : Hirose Yoshiaki

Page 1 of 6

It is certified that error appears in the above-identified patent and that said Letters Patent is hereby corrected as shown below:

On the Title Page

Replace the Title Page with attached Title Page displaying new Figure 1; and

In the Drawings

Replace sheets 1-4 with the attached Figures 1-4.

Signed and Sealed this
Eighteenth Day of July, 2017

Joseph Matal

(57) CLAIM

The ornamental design for graphite sheet for protecting
crucible, as shown and described.

DESCRIPTION

FIG. 1 is a front elevational view of the design, the rear
elevational view being the same;FIG. 2 is an elevational view of one side thereof, the other
side being the same;

FIG. 3 is a top plan view thereof;

FIG. 4 is a bottom plan view thereof; and,

FIG. 5 is an enlargement of rectangle 5 as shown in FIG. 1.
The broken lines in the drawings are for the purpose of
illustrating environmental structure and form no part of the
claimed design embodiments.
